UNITED STATES PATENT OFFICE.

HENRY C. BROWN, OF BROOKLYN, NEW YORK, ASSIGNEE OF ONE-HALF TO HENRY STOCKMAN, OF ENGLEWOOD, NEW JERSEY.

WASHERLESS FAUCET.

Specification of Letters Patent.

Patented Aug. 26, 1913.

1,071,294.

Application filed July 24, 1912. Serial No. 711,197.

To all whom it may concern:

Be it known that I, HENRY C. BROWN, a citizen of the United States, residing in the borough of Brooklyn, county of Kings, State of New York, have invented a new and useful Washerless Faucet, of which the following is a specification.

The object of my present invention is to devise a novel construction of a faucet or valve wherein I am enabled to dispense with the necessity of employing a washer in order to maintain a fluid tight seal between the valve and its seat.

With the above and other objects in view, which will hereinafter more fully appear in the detailed description, my invention consists of a novel construction and arrangement of a washerless faucet.

It further consists of a novel construction of a faucet wherein the valve is provided with means for positively locking the same in closed position, such valve being, at all times, exposed to the pressure of the fluid in such a manner that the pressure of the fluid exerted against the valve tends to move the same toward its seat.

It further consists of a novel construction of a valve seat, a novel construction of valve co-operating therewith and novel means for regulating the position of said valve.

Figure 1 represents a sectional elevation of a washerless faucet embodying my invention, the valve being shown in open position. Fig. 2 represents a sectional view similar to Fig. 1, but showing the valve and its adjuncts in the position they assume when the valve is in closed and locked position. Fig. 3 represents a section on line $\alpha-\alpha$, Fig. 1.

Similar numerals of reference indicate corresponding parts in the figures.

Referring to the drawings:—The valve body or casing comprises two parts 1 and 2, respectively, which have threaded engagement with each other as at 3. The casing member 1 is provided with a threaded extension 4, thereby adapting the same to be connected with any desired source of fluid supply, which enters the valve through the inlet 5. The member 1 is provided with an enlarged chamber 6, with which the inlet 5 communicates, and within this chamber 6 is mounted a valve 7 of novel construction. This valve 7 is provided with an incavated seat engaging portion 8 and is centrally re-

cessed as is indicated at 9, while the outer face of the valve is rounded as indicated at 10, it being apparent that the rear face of the valve is subjected to the pressure of the fluid entering the inlet 5 at all times, whereby the valve will automatically move toward its seat in the manner hereinafter described.

11 designates the outlet which communicates with a passage 12 which latter, when the parts are in assembled position opens 65 into the chamber 6 in the casing member 1, and through this passage 12 extends the valve spindle 13 which is in threaded engagement at 14 with the casing member 2.

15 designates an actuating handle secured 70 to the valve spindle 13. The forward end of the valve spindle 13 is preferably rounded and in proximity to such end the spindle is slotted as is indicated at 16.

In order to secure the valve 7 in operative condition with respect to the valve spindle 13, I provide a pin 17 which passes through the valve 7, and through the recess 9 therein, and also through the slot 16 in the valve spindle 13. The inner face of 75 the casing member 2 surrounding the passage 12, forms a valve seat 18, and is preferably rounded as shown in the drawing.

In the operation of my invention, assuming that the parts are in the position seen 85 in Fig. 2, it will be seen that the valve 7 is locked in closed position, since the pin 17 is seated at the outer end of the slot 16. When the spindle 13 is moved inwardly the inner end thereof contacts with the rear 90 wall of the recess 9, thereby causing the valve 7 to move away from the seat 18 and permit the fluid to pass from the inlet 5 to the outlet 11. As the valve moves toward its seat due to the rotation of the spindle 13, 95 it will be seen that the pressure of the water also tends to force the valve into contact with the seat, and as the stem is now free from the valve, except for the pin passing through the slot 16 it will be seen that the 100 only action which it imparts to the valve is a rotary movement, which action is continued until the back of the slot 16 engages the pin 17 and completes the closing of the valve by drawing the same tightly against the seat, thus locking such valve in closed position. This rotary movement of the valve while it is held against the seat only by the force of the water tends to cause the 105 faces of both the valve and the seat to ex- 110

- actly conform to each other and also grinds up the obstacles ordinarily present in the fluid. The spherical form of the valve also provides a larger and more complete contact and eliminates in a very large measure, the injury which is liable to be caused by a very hard substance, and also positions the valve for the pull exerted thereagainst by the threaded spindle 13.
- 10 Special attention is directed to the fact that in my present invention I have entirely eliminated the necessity of employing a packing or gasket in order to maintain a fluid tight seal between the valve and its seat, and I am thereby enabled to entirely eliminate the necessity of continuously re-packing the valve at frequent intervals, such as is necessary when the ordinary types of faucets are employed.
- 15 It will be apparent that in my present invention, I have reduced to a minimum the number of parts of the device, and since the same may be formed of castings it will be apparent that devices, in accordance with 20 my invention, may be very economically manufactured.
- It will now be apparent that I have devised a novel and useful construction of a washerless faucet which embodies the features of advantage enumerated as desirable 25 in the statement of the invention and the above description, and while I have, in the present instance, shown and described preferred embodiments thereof which have been 30 found in practice to give satisfactory and reliable results, it is to be understood that the same are susceptible of modification in various particulars without departing from the spirit or scope of the invention as stated 35 in the claims or sacrificing any of its advantages.
- Having thus described my invention, what I claim as new and desire to secure by Letters Patent, is:—
- 40 1. A valve comprising a casing having a

rounded seat, a spindle mounted for movement through the seat, a valve proper mounted for pivotal movement with respect to said seat and having an incavated face adapted to close against the seat, and means 50 connecting the spindle with the valve proper whereby the said parts are constrained to rotate in unison with each other but may move longitudinally of the spindle independently of each other.

2. A valve comprising a casing having a rounded seat, a spindle having a slot at one end and mounted for movement through the seat, a valve proper mounted for pivotal movement with respect to said seat and having 55 an incavated face adapted to close against said seat and having a recess to receive the end of the spindle, and a pin secured to the valve proper and passing through said slot and capable of movement 60 therein longitudinally of said spindle whereby said valve and spindle rotate in unison but are capable of relative movement longitudinally of the spindle independently of each other.

3. A valve comprising a casing having a rounded seat, a valve proper having an incavated face adapted to close against said seat and its opposite face exposed to the incoming liquid, said valve proper having a 70 recess in its incavated face, a spindle mounted for movement through said seat and having its end adapted to abut against the rear wall of said recess to move the valve proper away from said seat, said spindle having a 75 slot longitudinally thereof near one end, and a pin passing through said slot and secured to said valve whereby the valve proper and stem are capable of relative pivotal and longitudinal movement but are constrained to 80 rotate in unison.
